UNITED STATES PATENT OFFICE.

CHARLES A. NELSON, OF UTICA, NEW YORK, ASSIGNOR TO SAVAGE ARMS COMPANY,
OF UTICA, NEW YORK, A CORPORATION OF NEW YORK.

FIREARM.

1,080,364.

Specification of Letters Patent.

Patented Dec. 2, 1913.

Application filed October 15, 1912. Serial No. 725,949.

To all whom it may concern:

Be it known that I, CHARLES A. NELSON, a citizen of the United States, residing at Utica, in the county of Oneida and State of New York, have invented certain new and useful Improvements in Firearms, of which the following is a specification.

This invention relates particularly to safety locking devices for firearms.

10 It has for its object to provide a fire-arm with a simple and reliable safety locking means, this object having been carried out in the specific form of the invention shown and described herein with reference to the 15 trigger of an arm of the kind illustrated, for instance, in the patent to Searle No. 936,369 wherein is employed a device for locking the breech bolt and the firing mechanism, which device I utilize as a means for controlling the detent which I use for locking the trigger.

20 Referring to the accompanying drawings, Figure 1 is a side elevation of the improved arm, somewhat enlarged and partly in section; Fig. 2 is a rear elevation, partly in section; Fig. 3 is a sectional view on the line $\alpha-\alpha$ of Fig. 1; and, Fig. 4 illustrates a detail.

The frame α having the hollow grip b ; 30 the barrel c ; the breech-bolt d having the removable plug e forming therewith a breech structure which slides on the frame back and forth under the counter influences of the explosion-pressure and a spring (not shown); the firing-mechanism arranged in the plug e and including the cocking-lever f ; the firing-mechanism-releasing means including the trigger g arranged to slide backward and forward in the frame, and the 40 locking device consisting of a spindle h journaled in the frame and having a handle i and being adapted when turned to the dotted line position in Fig. 1 both to leave the breech mechanism free to move longitudinally and the cocking lever f free to move 45 against the firing-pin (because at that time a lug j of the firing lever coincides with a cross cut slot k in the spindle h) and being further adapted, when turned into the full 50 line position in Fig. 1, to be received by the one or the other of notches (not shown) in the breech-bolt to lock the breech mechanism against longitudinal movement and to oppose firing movement of the cocking lever 55 (because its slot k is not in registry with lug

j , which then impinges against the spindle), are or may be all substantially the same as in the patent to Searle, above mentioned.

60 l is the cartridge magazine adapted to be entered into the grip b from the bottom and suitably held therein.

The spindle h has an angular surface m (Fig. 4) against which bears a spring-pressed plunger n set in a housing o within the frame, the object of which is to urge the 65 lever, after passing the mid-position between the two stops p therefor, toward that stop which it is approaching and there securely hold it. This means, *per se*, I do not claim herein. Back of the magazine is arranged 70 a horizontal pin q which is held suitably against longitudinal displacement. On this pin is fulcrumed a lever constructed as follows: In plan, said lever conforms substantially to the inside contour of the grip b in 75 the plane of the section line $x-x$, it being a steel piece bent to the shape stated. Upwardly from its fulcrum portion extends an arm t , having a laterally projecting lug u affording means whereby to move the lever, 80 which is thus a lever of the first class. At its forward portion the lever is formed with the bend v which projects into an aperture w opening forwardly from the interior of the grip at a point back of the trigger g . 85 The trigger has a rearwardly projecting lug x , and the bend and lug are formed with coinciding faces y arranged approximately at a right angle to a radius from the axis of movement of the lever. The lug u plays in a 90 slot z in the frame, the end of which forms a stop limiting the relatively backward movement of the lever past the position shown in full lines in Fig. 1, and against this stop a spring 3 , coiled about the pin q and 95 having one end engaged with the grip b and the other end engaged with the extension t of the lever, normally tends to hold the lever. In the full line position of the locking device, including spindle h , the lever s therefore serves as a detent to lock the trigger against movement. When the said locking device is moved to the dotted line position its spring plunger, overcoming the tension of spring 3 , causes said device to 100 move the lever s to the dotted line position in Fig. 1, thus leaving the trigger free to be drawn rearwardly to release the firing-mechanism. One locking device (h) therefore 105 controls the other (s), and when the former 110

is in locking or unlocking position the latter is in the same position. It will be apparent that the divided or loop-shaped form of the lever *s* allows the magazine to be entered to 5 and removed from the housing therefor in the grip without interference.

Having thus fully described my invention, what I claim as new and desire to secure by Letters Patent is:—

- 10 1. In combination with a gun having a firing mechanism, means for releasing said mechanism and a locking device for said mechanism movable to locking and unlocking relation thereto, a detent movable independently of said device to locking and unlocking relation to said means and controlled by said device, substantially as described.
- 15 2. In combination with a gun having a firing mechanism, means for releasing said mechanism and a locking device for said mechanism movable to locking and unlocking relation thereto, a pivoted detent movable to locking and unlocking relation to said means and controlled by said device, substantially as described.
- 20 3. In combination with a gun having a firing mechanism, means for releasing said mechanism and a locking device for said mechanism movable to locking and unlocking relation thereto, a detent normally held in and movable out of locking engagement with said means and projecting in the path of movement of and actuatable by the locking device, substantially as described.
- 25 4. In combination with a gun having a firing mechanism and means for releasing said mechanism, a detent movable into and out of locking engagement with said means and a locking device for the firing mechanism movable into and spring-pressed against and adapted to move said detent, substantially as described.
- 30 5. In combination with a gun having a firing mechanism and means for releasing said mechanism, a detent movable into and out of locking engagement with said means and normally held in locking engagement therewith, and a locking device for the firing mechanism movable into and spring-pressed against and adapted to move said detent, substantially as described.
- 35 6. In combination with a gun having a

firing mechanism, means for releasing said mechanism and a locking device for said mechanism movable to locking and unlocking relation thereto, a two-armed lever fulcrumed in the gun and having one arm movable into and out of locking relation to said means and the other engageable by the locking device, substantially as described. 55 60

7. In combination with a gun having a frame, a firing mechanism and means for releasing said mechanism, and also having a fixed stop on the frame, a detent bearing 65 against the stop and thereby opposing movement of said means but movable out of engagement with said stop to allow movement of said means, and an actuating device movable against said detent and adapted to move 70 the same, substantially as described.

8. In combination with a gun having a frame, a firing mechanism and means for releasing said mechanism, and also having a fixed stop on the frame, a detent normally held bearing against the stop and thereby opposing movement of said means but movable out of engagement with said stop to allow movement of said means, and an actuating device movable against said detent and 75 adapted to move the same, substantially as described.

9. In combination with a gun having a firing mechanism, means for releasing said mechanism, and a locking device for said mechanism, a locking detent for said means controlled by said device and movable independently thereof, substantially as described. 85

10. In combination with a gun having a frame and mechanism for exploding the charge, a detent obstructing the movement of a movable part of said mechanism and movable out of obstructing relation to said part, a spring normally retaining said detent 95 in the movement obstructing relation of said part, and an actuating device spring-pressed against said detent to move the same, substantially as described. 90

In testimony whereof I affix my signature 100 in presence of two witnesses.

CHARLES A. NELSON.
